UNITED STATES PATENT OFFICE.

CHARLES E. BROWN, OF LAWTON, OKLAHOMA.

ORE-SEPARATOR.

1,254,651.

Specification of Letters Patent. Patented Jan. 29, 1918.

Application filed March 27, 1917. Serial No. 157,614.

To all whom it may concern:

Be it known that I, CHARLES E. BROWN, a citizen of the United States, residing at Lawton, in the county of Comanche and 5 State of Oklahoma, have invented certain new and useful Improvements in Ore-Separators, of which the following is a specification, reference being had to the accompanying drawings.

10 This invention relates to certain improvements in ore separators and has relation more particularly to a device of this general character especially designed and adapted for use in connection with metals such as 15 gold, silver and the like; and it is an object of the invention to provide novel and improved means whereby the values may be quickly and efficiently separated from auriferous or other material.

20 It is also an object of the invention to provide a separator of this character including novel and improved means whereby the value containing material is initially subjected to a thorough agitation to effect a 25 separation of the values and whereby the heavier concentrates resulting from this initial operation are subjected to a further agitation to effect a separation of the remaining values carried thereby.

30 The invention also has for an object to employ a trap of novel and improved construction and positioned as desired for collecting the values or concentrates as the same pass thereover.

35 A still further object of the invention is to provide a novel and improved separator of this general character including a plurality of coacting disks mounted for vibratory movement for agitating the value bearing 40 material discharged thereon and provided with means whereby the separated values may be collected. It is also an object of the invention to employ in connection with said disks novel and improved means 45 movable independently thereof for further agitating the value bearing material.

The invention consists in the details of construction and in the combination and arrangement of the several parts of my improved separator whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view partly in side elevation and partly in section of the vibrating mechanism constructed in accordance with the present embodiment of my invention;

Fig. 2 is a sectional view taken substantially on the line 2—2 of Fig. 1;

Fig. 3 is an enlarged detail sectional view taken through one of the concentrating members as shown in Figs. 1 and 2 and also 70 illustrating a trapping device as herein embodied;

Fig. 4 is a vertical sectional view taken through a disk and a coacting trap as herein included, said section being at substantially right angles to the section shown in Fig. 3;

Fig. 5 is a sectional view taken substantially on the line 5—5 of Fig. 3; and

Fig. 6 is a detached view in top plan of 80 one of the rotary troughs as herein disclosed.

As herein disclosed, 54 denotes a hopper adapted to receive heavy material or concentrates and has leading therefrom the 85 chutes 56 discharging upon the pans 57 coacting with the disks 58, and said material is then carried to the pans 57 carried by the disks 60 arranged at a predetermined point below the disks 58, hereinbefore referred to. 90 As the construction and mounting of each of the pans 57 and disks 58 are substantially identical, it is thought that a description of one will suffice for the purpose of disclosure.

95 61 denotes an annular trough having in communication therewith a chute 62 delivering to a pan 57 adjacent thereto or serving as a discharge for the waste or refuse material. The trough 61 also serves as a mounting for a disk 58 which is substantially concave and having its lower central portion provided with the discharge opening 63 defined by a depending boss 64 with which coacts a trapping device T. The pan 57 is also concave and fits within the disk 58 100 and has its central lower portion provided with a discharge opening 65 defined by a depending flange 66 which extends through the opening 63 of the disk 58 and within the boss 64.

As herein disclosed, a trapping device T is arranged beneath each of the depending bosses 64, the bore of said boss 64 being under control of the slide valve 38. As herein embodied, the boss 64 is provided with the outstanding arm 39 provided with the depending perforate ears 40 through which a threaded bolt 41 is directed, said bolt 41 having threaded thereon a nut 42 positioned 10 between the perforate ears 40 and the face of the nut 42 coacting with the arm to prevent rotation thereof. The outer end of the bolt 41 is provided with a fixed collar 43 positioned between the depending perforate ears 44 depending from the outer end of the arms 45 extending from the slide valve 38 and through which the bolt 41 is freely directed. The outer end of the bolt 41 is provided with an operating member 46, where- 20 by it will be perceived that upon axial rotation being imparted to the bolt 41, the slide valve 38 may be adjusted into either open or closed position relative to the bore of the boss 64. The boss 64 is also provided 25 with a flange 47 with which are operatively engaged the tie rods 48 adapted for detachable engagement with the base portion 49 of the cylindrical container 50 comprised in my improved trapping device T.

30 Snugly fitting within the container 50 is a head 51 mounted upon the rod 52 threaded through the base 49 of the container 50 and provided at its lower end with an operating member 53 whereby it will be 35 perceived that the position of the head 51 may be vertically adjusted.

Normally the head 51 is positioned slightly below the lower end of the boss 64 and as the values are collected therein, the 40 head 51 is adjusted downwardly and said adjustments are continued until the container 50 is substantially filled, whereupon the container 50 is removed and properly emptied and then replaced, or if desired, 45 a second container may be employed.

Each of the annular members 61 is operatively supported by a frame F suspended in operative position through the medium of the hangers H depending from the blocks 50 B carried by the upper portion of the skeleton frame 55. The frame F is adapted to be oscillated in order to properly agitate or vibrate the material within the pans 57 and 59, and as herein disclosed, the frame 55 is provided with a vertically disposed shaft 67 having an eccentric portion or crank 68 on which is loosely mounted a head 69 provided with the arms 70. Pivotal- 60 ly engaged with the arms 70 are the levers or pitmen 71 which are also pivotally engaged, as at 71^a, with the lower portion of the frame F whereby it will be perceived that as the shaft 67 is rotated, the frame F will be oscillated and the material within 65 the pans 57 and 59 effectively agitated. As

herein disclosed, each of the levers or pitmen 71 is in two sections with the adjacent extremities of said sections adjustably connected, as at 72, for a purpose which is believed to be clearly apparent to those skilled in the art to which my invention appertains.

As herein disclosed, the pan 57 in its upper surface is provided with a lining or perforate fabric 73 preferably coarse wire 75 gauze, and over which is placed a layer 74 of soft porous fabric preferably cloth matting, whereby it will be perceived that the fine flour gold or other fine metals may percolate into the fiber of the same. Most 80 of the flour gold or fine metals will pass through the fabric 74 and through the perforate fabric 73 and then down the walls of the pan 57 so that the values will pass through the opening 63 into the trapping 85 device T. If desired, the pan 57 may be made of copper metal and coated with quicksilver so as to act in amalgamation to a perfect and successful operation. It is preferred that the marginal portions of the 90 fabric 74 be protected by the annular member 75 preferably of heavy screen wire and which also serves to maintain the fabric in applied position.

It will be readily understood that when a 95 complete clean-up is desired, the pan 57, the trapping device T and the fabrics 73 and 74 may be all separately removed and a clean duplicate substituted so that no delay may be afforded during the operation of 100 the entire machine.

It is to be understood that a fresh supply of water is delivered to the material at the time it enters the hopper 54 and it will be perceived that the lighter material will 105 pass over the top of the pan 57 into the annular trough 61 for a purpose which is believed to be self-evident.

I have also found it of advantage to employ in connection with each of the pans 110 57 an independently operable agitating member herein disclosed as a cross arm 76 suitably secured to the lower end of a vertical shaft 77 rotatably supported by the frame 55, and the cross arm 76 is provided 115 with a plurality of depending fingers 78 of varying lengths so as to conform to the cross section of the pans 57.

The upper extremity of the vertical shaft 77 is operatively engaged, as at 79, with a horizontally disposed shaft 80 rotatably supported by the upper portion of the frame F and the shaft 80 is operatively engaged, as at 81, with a second shaft 82 which in turn is operatively engaged, as at 83, with 120 the shaft 84 carried by the lower portion of the machine, said shaft 84 being adapted to be coupled as indicated at 85, with any suitable source of power. The shaft 84 is also operatively engaged, as at 86, with the 130

vertical shaft 67, whereby the requisite axial rotation may be imparted thereto.

It is also to be observed that a disk or cover member 87 is supported above each 5 of the pans 57 and the agitating means co-acting therewith. The cover or lid 87 is disk-like in top plan to conform to the configuration in top plan of the disk 58 but is of a diameter less than that of the upper 10 portion of the disk 58 so that the lid or cover 87 may partially extend within the upper portion of the disk 58. This in practice has been found of utmost importance as the lid or cover 87 serves as a guard or 15 shield to prevent the air currents or liquid from entering within the bowl of the disk 58 which would otherwise result in flotation of the concentrates or value bearing material collected within the trap T or in the 20 lining as afforded by the fabrics 73 and 74. By having the cover member or disk 87 of a less diameter as just described, it will be at once self-evident that an annular opening is afforded for the passage or discharge 25 of the lighter or waste material. The central portion of the cover member 87 is provided with the upstanding hopper 88 into which discharges a chute 56 or a chute 62.

As herein disclosed, the cover member 87 30 is supported in applied position through the medium of the arms 89 radiating therefrom and operatively engaged with the upstanding side board 90 secured to the outer flange of the annular trough 61.

It is to be noted that each of the shafts 35 77 extends within the compartment afforded by the annular flange 66 and the portion of said shafts 77 within said chamber is provided with a series of spirally arranged out-standing fingers 91 which serve as a means for agitating the value containing material collected therein.

From the foregoing description, it is thought to be obvious that a separator constructed in accordance with my invention 45 is of an extremely simple and comparatively inexpensive nature and is particularly well adapted for use by reason of the convenience and facility with which it may be assembled, and it will also be obvious that my invention 50 is susceptible of some change and modification without material departure from the principles and spirit thereof and for this reason I do not wish to be understood as 55 limiting myself to the precise arrangement and formation of the several parts herein shown in carrying out my invention in practice, except as hereinafter claimed.

I claim:

60 1. A machine for separating ore comprising an annular trough mounted for vibratory movement and having a discharge chute leading therefrom, a substantially 65 concave disk supported by the annular trough and surrounded thereby and pro-

vided in its lower central portion with a discharge opening, a depending boss carried by the disk and defining said discharge opening, a collecting container detachably engaged with the lower end portion of the 70 boss, and agitating means co-acting with the disk and extending within the boss depending therefrom.

2. A machine for separating ore comprising 75 an annular trough mounted for vibratory movement and having a discharge chute leading therefrom, a substantially concave disk supported by the annular trough and surrounded thereby and provided in its lower central portion with a discharge opening, a depending boss carried by the disk and defining said discharge opening, a collecting container detachably engaged with the lower end portion of the boss, and agitating means co-acting with the disk and extending 80 within the boss depending therefrom, a cover member supported by the trough and overlying the disk, and an upstanding hopper carried by the cover member and discharging within the disk at the 85 axial center thereof.

3. A machine for separating ore comprising 90 an annular trough mounted for vibratory movement and having a discharge chute leading therefrom, a substantially concave disk supported by the annular trough and surrounded thereby and provided in its lower central portion with a discharge opening, a depending boss carried by the disk and defining said discharge 95 opening, a collecting container detachably engaged with the lower end portion of the boss, agitating means co-acting with the disk and extending within the boss depending therefrom, a cover member supported by the trough and overlying the disk, and an upstanding hopper carried by the cover member and discharging within the disk at the 100 axial center thereof, said cover member being flat and arranged substantially at 105 right angles to the axial center of the disk.

4. A machine for separating ore comprising 110 an annular trough mounted for vibratory movement and having a discharge chute leading therefrom, a substantially concave disk supported by the annular trough and surrounded thereby and provided in its lower central portion with a discharge opening, a depending boss carried by the disk and defining said discharge opening, 115 a collecting container detachably engaged with the lower end portion of the boss, agitating means co-acting with the disk and extending within the boss depending therefrom, a slide valve co-acting with the depending box for controlling travel there-through, and means carried by the boss for imparting endwise movement to the valve. 120

5. A machine for separating ore comprising 125 an annular trough mounted for vibratory movement and having a discharge chute leading therefrom, a substantially concave disk supported by the annular trough and surrounded thereby and provided in its lower central portion with a discharge opening, a depending boss carried by the disk and defining said discharge opening, a collecting container detachably engaged with the lower end portion of the boss, agitating means co-acting with the disk and extending within the boss depending therefrom, a slide valve co-acting with the depending box for controlling travel there-through, and means carried by the boss for imparting endwise movement to the valve.

6. A machine for separating ore comprising 130 an annular trough mounted for vibratory movement and having a discharge chute leading therefrom, a substantially concave disk supported by the annular trough and surrounded thereby and provided in its lower central portion with a discharge opening, a depending boss carried by the disk and defining said discharge opening, a collecting container detachably engaged with the lower end portion of the boss, agitating means co-acting with the disk and extending within the boss depending therefrom, a slide valve co-acting with the depending box for controlling travel there-through, and means carried by the boss for imparting endwise movement to the valve.

tory movement and having a discharge chute leading therefrom, a substantially concave disk supported by the annular trough and surrounded thereby and provided in its lower central portion with a discharge opening, a depending boss carried by the disk and defining said discharge opening, a collecting container detachably engaged with the lower end portion of the boss, agitating means co-acting with the disk and extending within the boss depending therefrom, a cover member supported by the trough and overlying the disk, an up-

standing hopper carried by the cover member and discharging within the disk at the axial center thereof, said cover member extending within the disk and the major diameter of the cover member being less than the mean diameter of the upper portion of the disk.

In testimony whereof I hereunto affix my signature in the presence of two witnesses.

CHARLES E. BROWN.
